KEY HOLDER AND PROTECTOR

Robert E. Jackson, Dedham, Mass.

Application April 13, 1940, Serial No. 329,585

8 Claims. (Cl. 70—447)

This invention relates to devices for containing keys and preventing unauthorized use thereof, and more particularly to the containing of house or apartment keys.

The principal objects of the invention include the provision of a housing, having a combination lock, for a house key, said housing to be mounted on a house door, or in some other convenient place, so that an authorized person having the combination, may gain access to the house or other locked structure; the provision of such a housing having a drop shelf or drawer which contains the key and drops upon proper manipulation of the combination; and the provision of a key holder and protector of simple design and effective in operation, having safety features to prevent unauthorized removal of the key or the holder itself.

Other objects and advantages of the invention will appear hereinafter.

Reference is to be had to the accompanying drawing, in which

Fig. 1 is a front elevation of the device with drawer closed;

Fig. 2 is a view similar to Fig. 1, but showing the drawer open;

Fig. 3 is a side elevation of the parts of Fig. 1;

Fig. 4 is a side elevation of the separable front element of the housing;

Fig. 5 is a rear elevation of the housing, looking in the direction of arrow 5 in Fig. 3;

Fig. 6 is a rear elevation of the parts shown in Fig. 4, and looking in the direction of arrow 6 in that figure;

Fig. 7 is a sectional view on line 7—7 of Fig. 2;

Fig. 8 is a sectional view on line 8—8 of Fig. 7; and

Fig. 9 is a detail view of a screwhead guard.

The numeral 10 indicates a front plate having side flanges 12 and an inverted V-shaped top flange 14, to fit in and coincide with the similarly shaped roof 16 of the housing proper 18. The plate 10 is secured to the housing 18 by means of long screws 20 which engage in raised threaded bosses 22 on the rear plate 24 of the housing.

The sides 26 of housing 18 provide guideways for the reception of a slidable drawer 28 which, however, is connected to the front plate 10 for vertical sliding action thereon. The bottom of housing 18 is open, and the bottom of the drawer 28 closes the same when the latter is in raised or locked position.

The drawer is enclosed on all sides except the front. Two spaced posts 30 rise from the top of the drawer, and form further guides for the drawer movement as they slidely engage raised elements or studs 32 which are integral with the back of the plate 10. Between posts 30 there is a plate 34 extending from the top of

the drawer part way up the posts. The drawer 28, posts 30, and plate 34 are all made integral in one piece.

Plate 34 carries on its rear face a combination lock 36, the dials 38 of which extend thru an aperture 40 in the plate 10 to the front thereof, so that they may be manipulated thru a hinged door 42 in the plate when the drawer is in up or locked position. A shelf 44 having two depending hooks 46 constitutes a latch for the lock, where when the drawer is up, and the hooks are engaged, the parts are locked, and the front plate 10 of course prevents access to the key. A lip 48 extending forwardly from the top of plate 34 prevents entire removal of the drawer 28 by engagement with the bottom of the door opening in plate 10.

Plates 50 are secured to the studs 32 by screws 52, and screws 20 are rotatably mounted in these plates and held against axial movement by nuts 54, to extend rearwardly for engagement with the bosses 22, so as to secure the front plate 10 to the housing 18. When door 42 is open, the heads of screws 20 are revealed, and can be turned by a screwdriver.

Plates 50 constitute an enclosure on plate 10 to retain the plate 34 and posts 30 and thus the drawer 28, so that together with lip 48, the drawer 28, although slidingly mounted on plate 10, cannot be removed therefrom without removing screws 52 and plate 50 from the studs 32. These elements being on the rear of plate 10, it will be clear that the plate 50 cannot be removed without first removing the plate 10 from the housing 18.

Referring to Fig. 9, which shows the top part of a plate 50, there is a pin 56 set into the plate and this pin is spaced from the top screw 52. A thin plate 58 is swingingly mounted on the pin 56 so as to cover the head of the screws 20 in the relation shown in Fig. 9. The purpose of this plate is to conceal the heads of screws 20 from the observation of a person who opens the door 42 and correctly manipulates the dials of the combination lock to let the drawer 28 drop, since otherwise the screw heads will be apparent, and as a matter of fact, the screw heads can be turned by a screwdriver only thru the door as will be apparent from the arrangement of the parts, as shown in Fig. 7. The plates 58 being pivoted on the pin 56 may be swung up to reveal the screw heads of the screws 20 by a person who is aware of their secret. Plates 58 are cut away at the corners as shown, in order to avoid impinging on the screws 52.

The door 42 is provided with bosses 60 which are apertured to receive hinge pins 62, and as seen in Fig. 7, boss 60 is curved at the edge of the door to ride on the plate 34 when the door is swung open. A pin or set screw 64 is mounted

to project from the boss 60 and a cooperating slot 66 is provided in the plate 34 at a point where the pin 64 will engage in the slot when the drawer 28 is in its upward-most position and when the door is open. However, if the door is unlocked and the lock is not engaged with its hooks 46, the drawer may descend.

In the operation of the device, the housing 18 is secured to any support desired by screws or bolts passing thru the slots 68 shown in Fig. 5, and then the completely assembled front plate 10 and drawer 28 are positioned within the housing so that the screws 20 align with the threaded bosses 22. The drawer 28 is dropped, the hinge plates 58 are swung up to reveal the heads of the screws 20, and by simple manipulation of a screwdriver, the assembled plate and drawer are secured to the housing 18. The hinge plates 58 are swung into position to conceal the heads of the screws 20, the door 42 is shut, and the drawer 28 is thrust up from the bottom so as to engage and lock with the hooks 46.

It will be apparent from the above that the protective housing may be secured at some convenient location on the outside of a house or dwelling and the key to the house may be located in the compartment in the drawer. The device being locked, an authorized person knowing the combination may swing open the door 42, manipulate the dials of the lock to unlocking combination, and then upon closing the door and releasing the pin 64 from the slot 66, the drawer will drop revealing the key. In order to close and relock the device, it is only necessary to close the door 42 and push the drawer upwards into locking engagement with the hooks 46. The door can then be opened and the dials on the lock changed.

It will thus be seen that the present inventor has produced a key holder and protector which may be applied to any dwelling or building to hold the key for the same so that the key will never become lost or forgotten. This device is particularly useful for rental or sales agents who may have a great number of houses to show prospects and who must carry or maintain in their offices a great number of separate keys. By using one of these key holders for each of their houses, such an agent does not have to be equipped with a key for each house or apartment but merely has to know the lock combination, and he may thus obtain access to and show all of his houses or buildings without the necessity of carrying a great number of keys.

Likewise professional people, such as doctors, who are called upon to leave their homes at all hours of the day or night for emergencies will not be forced to stop to remember to take their front door key with them, simply by using the device disclosed in the present application.

Having thus described my invention and the advantages thereof, I do not wish to be limited to the details herein disclosed, otherwise than as set forth in the claims, but what I claim is:

1. In a device of the class described, the combination of a housing, a vertically slidable container element therein; with lock means operatively connected between the housing and element to hold the latter in raised position, whereby upon unlocking said lock means, said element 70 will be caused to descend by gravity.

2. In a device of the class described, a housing having a front plate connected thereto, a vertically slidable drawer connected to said front plate, an aperture in said plate and locking

means having one locking element on said slideable drawer and the other locking element being mounted in fixed position on said housing, one of said locking elements being visible through said aperture when the drawer is in closed position, and means on said housing normally concealing said one locking element, whereby said locking means is adapted to hold said drawer against descent by gravity.

3. In a device of the class described, a housing having an open bottom, a vertically slideable drawer in said housing and projecting through said open bottom when extended, said drawer forming a bottom for the housing when closed, locking means operatively arranged between said drawer and said housing, an aperture in said housing through which said locking means is visible, means to close said aperture, and means on said drawer preventing complete removal thereof from said housing.

4. In a device of the class described, a housing, a vertically slideable drawer in said housing, locking means arranged between said drawer and said housing interiorly thereof, an aperture in said housing through which said locking means is visible, means to prevent removal of said drawer from said housing, said locking means being engaged when said drawer is fully contained within said housing, and guiding means in said housing for the sliding movement of said drawer.

5. In a device of the class described, a housing having a front plate, an aperture in said plate, a drawer slideable within the housing behind said front plate so as to be fully contained within the housing in closed condition thereof, a plate integral with said drawer and adapted to be visible through said opening when the drawer is closed, locking means extending through the plate on the drawer so as to be visible through the front plate aperture when the drawer is closed, and means in the housing cooperating with said locking means to lock the drawer in position when contained wholly within the housing, said means being capable of manipulation through said front plate aperture to disengage the locking means.

6. In a device of the class described, a housing having a detachable front plate secured thereto, an aperture in said front plate, screws mounted on the rear of said front plate so that the heads thereof are visible through said aperture, means on said housing to receive said screws to connect the front plate to the housing, and a slideable drawer in said housing and concealed by the front plate when in closed position.

7. In a device of the class described, a housing having a front plate and an open bottom, an aperture in said front plate and a door pivoted in said aperture to close the same, a sliding drawer arranged in said housing so as to close the bottom of said housing when the drawer is closed, a plate extending from said drawer and visible through the front plate aperture when the drawer is closed, a slot in said drawer plate and a lug on said door to engage in said slot when the drawer is closed and the door is open to prevent sliding movement outwardly of said drawer, except when said door is closed.

8. In a device of the class described, as recited in claim 6, in which the screw heads visible through said plate opening are provided with movable means to conceal the same.
